UNITED STATES PATENT OFFICE.

BENJAMIN F. KNELL, OF PHILADELPHIA, PENNSYLVANIA.

DESIGN FOR A COMBINED IMPLEMENT FOR STRINGED MUSICAL INSTRUMENTS.

58,768.

Specification for Design.

Patented Aug. 30, 1921.

Application filed April 12, 1921. Serial No. 460,820. Term of patent 14 years.

To all whom it may concern:

Be it known that I, BENJAMIN F. KNELL, a citizen of the United States, residing in the city and county of Philadelphia, State of Pennsylvania, have invented a new, original, and ornamental Design for Combined Implements for Stringed Musical Instruments, comprising a knife for string-cutting, a tweezer for string-threading, and a mute applicable to such instruments, of which the following is a specification, reference being

had to the accompanying drawing, forming part thereof.

The figure is a perspective view of a combined implement for stringed musical instruments, showing my new design.

I claim:—

The ornamental design for a combined implement for stringed musical instruments, as shown.

BENJAMIN F. KNELL.
